UNITED STATES PATENT OFFICE.

ROSA SCHOENHOLZ, OF SAN FRANCISCO, CALIFORNIA.

DESIGN FOR A HAIR-REMOVER.

49,626.

Specification for Design.

Patented Sept. 5, 1916.

Application filed July 5, 1916. Serial No. 107,712. Term of patent 3½ years.

To all whom it may concern:

Be it known that I, ROSA SCHOENHOLZ, a citizen of the United States, residing in the city and county of San Francisco and State of California, have invented a new, original, and ornamental Design for a Hair-Remover, of which the following is a specification, reference being had to the accompanying drawings, forming part thereof.

The figure is a side elevation of the device.

I claim:

The ornamental design for a hair remover, as shown.

ROSA SCHOENHOLZ.

Witnesses:

BEATRICE ABRAM,
GEO. H. STRONG.
